ASSIGNORS TO UNION CITY BODY COMPANY, A CORPORATION OF INDIANA

THEATER CHAIR

Application filed October 29, 1928. Serial No. 315,614.

The object of our present invention is to provide a theater chair structure composed of associated side sections, back sections, seat sections, and side trimming sections wherein, the side sections being angularly adjustable relative to the interposed back and seat in order that a series of seat units may be formed into a row of any desired curvature, the finish or trimming members, associable with the side members may have their exposed faces covered with any desired finish or ornamentation and of such construction as to be readily associative with the side members in such manner as not to be disturbable by the seat occupants and wherein the side finish elements will cover the junction between the back and side.

The accompanying drawings illustrate our invention:

20 Fig. 1 is a horizontal section of a structure embodying our invention;

Fig. 2 a vertical section through one of the sides, and

25 Fig. 3 an elevation of the inner or unexposed face of one of the side-finish inserts or plates.

30 In the drawings 10, 10 indicate the front and rear legs, and 11 the top bar, of a side unit of our chair, the legs 10, 10 and the top bar 11 being most conveniently integral and formed of angle iron.

Attached to the rear leg 10 is a sheet metal structure 12 having its opposite edges formed into semi-cylindrical pockets or troughs 13 each of said troughs being supported by an intermediate portion 14 of the body 12 in such manner that the troughs may be laterally flexed relative to the main body of the side unit. The intermediate portion 14 lies substantially parallel with the medial plane of the side unit and mounted in each trough is a mating edge portion of the back unit 15, said back unit 15 comprising a suitable upholstered, or otherwise finished, finish element 16.

50 A seat element is to be interposed between two adjacent side units but, as such seat element forms no part of our present invention it is not indicated in the drawings.

An arm rest 17 is secured to the cross bar 11 of the side unit.

In a structure such as has been thus far described it is desirable to provide some sort of a finish element to bridge the gap between the front and rear legs of the side unit below the arm rest 17 and above the plane of the seat, and the finish element which we have provided is of such character that, although it may be very readily placed, withdrawn, and replaced, it may not be accidentally displaced by the seat occupant and will be of such character as to cover the junction between the side unit and the back unit and may be made to blend in with the finish or exposed front face of the back.

This side unit finish member comprises a main body plate 20, conveniently of sheet metal, with its forward edge 20' turned substantially at right angles to the main plane of the plate and of such width and length as to bridge the space, below the cross bar 11 to a point somewhat below the upper edge of an intermediate cross bar 21 forming part of the side unit, and between the arm 22 of the front leg 10 and the forward edge of portion 14 of element 12, the rear edge of plate 20 projecting over this portion 14, substantially as shown in Fig. 1. Secured to plate 20, near its rear edge, conveniently by spot welding, or formed integrally therewith, if desired, is a curved lip 23 of sufficient extent to bridge over the junction between the side unit and the back unit and slightly overlie the upholstery 16 of the back unit 15. This finish plate 20—23 may have its exposed face finished or ornamented to conform to the other exposed finishes of the chair, and conveniently this may be accomplished by applying to the exposed face a sheet of fabric 24.

As a convenient means of retaining plate 21—23 in place we secure to the back, or unexposed face of plate 20 a downwardly extended hook or finger 27 adapted to extend into a slot or pocket 28 formed in the top of cross bar 21, said cross bar in the form shown in the drawings, being conveniently formed of a double sheet of metal 100.

secured at its front and rear edges to the legs 10.

The lip 23 being flexible it is apparent that its free edge may accommodate itself to the adjacent upholstery 16 in angular adjustments of the side unit relative to the back, such angular adjustments being permissible by reason of the flexibility of the portion 14.

10 The inturned edge 20' of plate 20 abutting against the inner vertical face of arm 22, and the rear edge of plate 20 abutting against portion 14, and hook 27 laterally interlocking with cross bar 21, and the upper edge 15 of plate 20 closely underlying arm 17, it is apparent that, when the parts have been assembled, as shown in the drawings, the side unit finish plate may not be accidentally displaced and is firmly retained in position.

15 We claim as our invention:

1. In a theater seat the combination of a back unit and a side unit connected together by means permitting horizontal angular adjustment of the side unit relative to the back 20 unit, a forwardly projecting finger carried by a side unit at its rear, a side unit finish element bridging across the side unit from rear to front above the seat plane and engaging the forwardly projecting lip and 25 having a portion projected over the junction between the side unit and back unit.

2. In a theater seat the combination of a back unit and a side unit connected together by means permitting horizontal angular adjustment of the side unit relative to the back 30 unit, a forwardly projecting finger carried by a side unit at its rear, a rearwardly facing surface carried by the side unit at its front, a side unit finish element bridging across the side unit from rear to front above the seat plane and engaging the forwardly projecting lip and the rearwardly presented face and having a portion projected over the junction between the side unit and back 35 unit.

3. In a theater seat the combination of a back unit and a side unit connected together by means permitting horizontal angular adjustment of the side unit relative to the back 40 unit, a forwardly projecting finger carried by a side unit at its rear, a side unit finish element bridging across the side unit from rear to front above the seat plane and engaging the forwardly projected lip and having a laterally flexible portion projected over the junction between the side unit and back 45 unit.

4. In a theater seat the combination of a back unit and a side unit connected together 50 by means permitting horizontal angular adjustment of the side unit relative to the back unit, a forwardly projected finger carried by a side unit at its rear, a rearwardly facing surface carried by the side unit at its front, 55 a side unit finish element bridging across

the side unit from rear to front above the seat plane and engaging the forwardly projected lip and the rearwardly presented face and having a laterally flexible portion projected over the junction between the side unit and back unit. 70

5. In a theater seat the combination of a back unit and a side unit, means for connecting said units, a side finish plate separably connected with the side unit, the rear portion of said plate extending over the junction between the side and back and being laterally flexible to compensate variations in horizontal angular relations between the back and side. 75

In witness whereof, CHARLES C. ADELSPERGER and HEBER D. FITZGERALD have hereunto set their hands at Indianapolis, Indiana, this 24th day of October, A. D. one thousand nine hundred and twenty eight. 80

HEBER D. FITZGERALD.
CHARLES C. ADELSPERGER.
